[57] CLAIM

The ornamental design for an animal feeder, as shown and described.

DESCRIPTION

FIG. 1 is an elevational view taken from one side of an animal feeder showing my new design, the opposite side being the same as the side shown;

FIG. 2 is a bottom plan view thereof;

FIG. 3 is a top plan view thereof; and

FIG. 4 is an elevational view taken from one end thereof, the opposite end being the same as the end shown.
